CLAIM

The ornamental design for a plant holder, as shown.

DESCRIPTION

FIG. 1 is a front isometric view of the plant holder of the present invention;

FIG. 2 is a rear isometric view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof; and,

FIG. 8 is a bottom view thereof.

1 Claim, 8 Drawing Sheets
